UNITED STATES PATENT OFFICE.

OTTO PALM, JR., OF RAHWAY, NEW JERSEY, ASSIGNOR TO THE PALM BROTHERS COMPANY, OF NEW YORK, N. Y., A CORPORATION OF OHIO.

DECALCOMANIA.

1,331,667.

Specification of Letters Patent. Patented Feb. 24, 1920.

Application filed November 26, 1919. Serial No. 340,720.

To all whom it may concern:

Be it known that I, OTTO PALM, JR., a citizen of the United States, residing at Rahway, in the county of Union and State of

5 New Jersey, have invented certain new and useful Improvements in Decalcomanias, of which the following is a specification.

This invention relates to decalcomanias, and has particular reference to decalcomania 10 stripes or borders upon which are provided a plurality of alined figures or designs, the object of the invention being to form a decalcomania stripe of this character in such manner that the designs or 15 figures when transferred may be placed in relatively angular or curved relationship with respect to each other, so that the decalcomania may be effectively employed for the purpose of decorating angled or 20 curved surfaces as well as for straight designs.

Straight decalcomania stripings or borders that have been used for years in decalcomania manufacture have only been of such 25 form as to be capable of being used, in the transfer of their designs, upon or in perfectly straight lines, whereas stripings or borders adapted for curves, angles or corners have been made and manufactured so 30 as to conform to the exact shapes of angles, curves or corners in order to make them fit and conform to such conditions.

By the present invention a perfectly straight border or striping may be used as 35 a straight border or striping, and the added functions being accomplished by cutting the decalcomania in accordance with guide or cutting lines provided upon the pattern surface of the decalcomanias, whereby the latter may be longitudinally flexed or distorted so that their designs may be so placed upon a surface as to permit of their angular or 40 curved disposition thereon.

A further object of the invention resides 45 in the provision of a decalcomania border or striping having provided thereon printing and pattern surfaces, the pattern surface being formed with cutting lines of triangular configuration, the apices of which 50 are so disposed as to project into the interstices formed between the alined designs or figures on printing surfaces, whereby upon the removal of the material defined by at least certain of said lines, said strip- 55 ing or border may be longitudinally twisted

to assume any desired position in order that the designs or figures may be imparted to a surface in straight, angular or curved relationship.

A still further object of the invention resides in providing the pattern surface with a plurality of longitudinally extending centrally disposed lines upon the outer of which the apices of the triangular cutting line terminate, said central lines being so disposed that when the material defined by the triangular cutting lines is removed, said central lines will serve to define a bonding medium for retaining the stripe as a whole together and yet to permit of the desired flexing of the same. 60

For a further understanding of the invention, reference is to be had to the following description, and to the accompanying drawing, in which: 75

Figure 1 illustrates the printing surface of a decalcomania border or striping, which is formed in accordance with the principles of the invention,

Fig. 2 represents the reference or pattern surface of the decalcomania and discloses more particularly the cutting line arrangement, 80

Fig. 3 illustrates the decalcomania when portions defined by the cutting lines have been removed, so that said decalcomania may be flexed to permit the designs thereof to be transferred in a relatively curved manner, 85

Fig. 4 is a view showing the application of the designs or figures when the decalcomania is cut in accordance with the showing set forth in Fig. 3, and 90

Fig. 5 is a view showing another manner for cutting decalcomania to permit the designs thereof to be transferred in a relatively angular manner. 95

Similar characters of reference denote like and corresponding parts throughout the several views of the drawing. 100

Referring more particularly to the details of the invention, use is made of a decalcomania border or striping which is designated in its entirety by the numeral 1. This decalcomania consists of a printing surface 105 2 upon which are transferably mounted a plurality of longitudinally alined figures or designs 3 of any suitable configuration, and it will be understood that these designs may be applied and transferred to any suitable 110

article or surface in the usual manner. In this instance the decalcomania has its opposite side formed with a pattern surface 4, upon which are provided fac-simile outlines 5 of the designs 3 provided upon the printing surface. The construction thus described is that which has been used in the past for the purpose of printing in straight lines, however, it has hitherto been impossible to employ such decalcomanias for the purpose of printing the designs in a relatively curved or angular manner, such designs in the past having been printed originally in the relatively curved or angular manner in which they were adapted to be placed upon the surface designed for their reception. However, through the provision of the features of the present invention, it is possible to employ straight decalcomania stripes not only for the purpose of producing straight designs but also of such construction as to be capable of accurately and easily producing the designs in a curved or angular manner and by this construction to enable a manufacturer and the trade at large to materially reduce varieties of forms in stock and to generally standardize the production of borders or stripings.

To this end, I provide the surface 4 with a plurality of centrally disposed longitudinally extending lines 6, which extend directly across the center portions of the designs 5, and which define as it will be later set forth, a bonding medium for the designs 3. In addition to the lines 6 use is made of a plurality of cutting lines 7, which define isosceles triangles, or they may be of other desirable configuration. The bases of the triangular wedges 8, defined by the line 7, are disposed along the outer marginal edges 9 of the decalcomania, while the apices thereof protrude between the interstices formed between the designs 3 or 5 and terminate upon the outer of the central lines 6. Other laterally extending lines 10 divide the wedges 8 into right angle triangles, and these lines 10 are so disposed as to extend from the central lines 6 to the edges 9.

By use of this construction it is possible to cut the decalcomania 1 in such manner as to permit of the longitudinal flexing of the same, so that the figures or designs 3 may be transferred in the curved manner disclosed in Fig. 4. This is accomplished by removing the wedges formed along the upper edge of the stripe, and these wedges are removed by cutting the stripes along the cutting lines 7 so that the material of said stripe may be removed in a V shape manner between the designs. Then, the lower edges of said stripe are slotted along the lateral lines 10 so that the desired flexibility may be imparted to the stripe 1. Manifestly, by removing the upper edges and in providing oppositely disposed slotted portions, the stripe as a whole

may be longitudinally distorted in the curved and flexed manner clearly set forth in Fig. 3, so that when the designs 3 are transferred the same will be positioned upon a surface in the curved manner disclosed in Fig. 4. By this construction it will be apparent that a straight border or striping may be so cut as to permit of the angular or curved disposition of the transfer designs, and the construction will thus eliminate the necessity of printing the designs initially in the desired curved manner. Also, as shown in Fig. 5, the designs may be transferred in an angular manner. This may be accomplished by removing wedges 8 from both of the edges or sides of a stripe 1, and in slitting the stripe laterally at positions opposite to the removed wedges. Obviously, this process will permit a border or striping to be angularly bent throughout its length so that the desired angular arrangement of the figures or designs 3 may be easily and positively effected.

It will be furthermore noticed that the cutting lines 7 for cutting the wedges or triangles and slits formed in the sheets, do not extend all the way across the border, but on the contrary only to the horizontal lines 6 which lie across the center of the border. The object of the lines 6 being to hold the entire border together in one piece during the transferring operation, so that the whole border may be transferred in one continuous piece or section in either a straight or curved manner. The invention is particularly applicable in the printing of decalcomania stripings or borders upon carriages, wagon and automobile bodies, sleighs, carts and other machinery having curved panels where straight borders and stripings will not answer hence, by cutting the straight border according to the guide outlines, any angle or curved border may be produced. Of course it will be apparent that the principles of this invention may be differently carried out from the specific form described, for example the cutting lines may be provided on the printing surface, if desired, instead of on the pattern surface, or that it is not necessary to adhere to the triangular outline shown in removing material from the decalcomania, as manifestly other configurations may be removed and the same result accomplished.

I claim:

1. A decalcomania comprising a printing surface and a pattern surface, said pattern surface bearing outlines representing the designs upon said printing surface, and cutting lines of triangular configuration provided upon said pattern surface and situated between the design outlines thereof, whereby upon the removal of material defined by at least certain of said cutting lines said decalcomania may be flexed to permit its de-

- signs to be transferred in a relatively angular or curved manner.
2. A decalcomania of stripe formation formed to comprise a printing surface, a plurality of designs provided upon said surface, and cutting lines located between said designs and by means of which material may be removed from the decalcomania to permit the latter to assume flexed positions, whereby the designs thereof may be transferred in a relatively angular or curved manner.
3. A decalcomania having a printing surface upon which is provided an elongated design, and cutting indicia provided upon said decalcomania and located contiguous to said design so as to extend into the marginal interstices thereof, whereby upon the removal of desired portions of the decalcomania defined by said indicia said decalcomania may be bent to permit its design to be transferred in a relatively angular or curved manner.
4. A decalcomania stripe comprising a printing surface, a plurality of aligned designs provided upon said surface, cutting
- lines defining triangular wedges disposed between said designs, whereby upon the removal of at least certain of said wedges, said decalcomania may be longitudinally distorted to permit said designs to be transferred in a relatively curved or angular manner.
5. A decalcomania border comprising a printing surface bearing a plurality of aligned transferrable figures, a pattern surface disposed on the opposite side of said decalcomania, said pattern surface bearing outline representations of the figure upon said printing surface, longitudinally extending lines arranged longitudinally and centrally of said border, and cutting lines disposed between figure outlines upon said pattern surface, said cutting lines being of triangular configuration and having their apices terminated adjacent to said longitudinally extending lines, said cutting lines serving to permit said border to be cut in such manner as to permit of its longitudinal distortion.

In testimony whereof I affix my signature.
OTTO PALM, JR.
